PORTABLE SHEET METAL BENDING
TOOL

Andrew M. Hexdall, Morris, Ill.

Application June 25, 1938, Serial No. 215,941

7 Claims. (Cl. 153—21)

The invention relates to sheet metal bending tools and more particularly to portable tools of this type which may, for example, be used to bend the marginal edge portions of metal sheets. 5 The general object of the present invention is to provide a tool of the type described which is thoroughly portable and embodies a self-contained power unit such that it may be readily carried to the work site and used without difficulty to operate upon sheet metal structures which may even be installed in a building and inaccessible to ordinary stationary sheet metal bending brakes or tools.

Another object of the invention is to provide 15 a tool of the type described so constructed that it may be readily applied by the operator to various parts of assembled or semi-assembled sheet metal structures without the necessity of moving the latter.

Still another object of the invention is to provide 20 a tool of the type described for quickly and effectively finishing Pittsburgh or similar joints at the juncture of two angularly disposed metal sheets in which finishing operation a marginal portion of a metal sheet must be bent through 25 a substantial angle, usually 90°, and pressed flat against the surface of one of the sheets.

Further objects and advantages of the invention will become apparent as the following description proceeds taken in connection with the 30 accompanying drawings in which:

Figure 1 is a side elevation of a tool embodying the present invention and shown as operating upon a sheet metal structure provided with 35 a Pittsburgh joint;

Fig. 2 is an enlarged vertical sectional view of the tool and sheet metal structure shown in Fig. 1;

Fig. 3 is an enlarged partial bottom plan view 40 of the tool shown in Fig. 1;

Fig. 4 is an enlarged front end elevation of the tool of Fig. 1 with the sheet metal structure operated upon shown in dot-dash lines;

Fig. 5 is a detail perspective view of the metal-bending plunger included in the tool.

The invention has been shown herein as embodied in a tool especially designed for finishing so-called Pittsburgh joints in sheet metal structures although it may, of course, be used, 50 or modified for use, in performing a number of other types of sheet metal bending operations. The tool has been shown herein as being utilized in the finishing of a Pittsburgh joint between two sheets of metal 10 and 11 (Fig. 2) which may, 55 for example, be part of an air conditioning con-

duit system. In fashioning the joint between the sheets of metal a reentrant bend is formed in the marginal portion of the sheet 11 as indicated at 12 and a laterally extending flange 13 on the sheet 10 is inserted into the recess formed 5 in the folded edge portion of the sheet 11. In finishing the joint, it is necessary to bend the edge or flange 14 on the sheet 11 from its upright position, shown in dot-dash lines in Fig. 2, through an angle of substantially 90° and to 10 press it smoothly against the surface of the sheet 10; in the position shown in full lines in Fig. 2. It is this finishing operation which the tool herein disclosed is particularly designed to accomplish. The portability of the tool is a highly important feature when the sheet metal structure is being erected in, or as a part of, a building so that at least the finishing operations must be carried out in locations which are comparatively difficult of access. Even when the sheet metal structure is erected in a shop, the bulk of the structure often renders it difficult, if not impossible, to utilize conventional stationary sheet metal working tools.

In the form of the invention illustrated the 25 tool includes an elongated body member or casting 15 sloping upwardly to terminate in a rounded rear or butt end to which is bolted an electric driving motor 16. The driving motor includes a 30 suitable cup shaped enclosing casing fast on the body casting 15. The lines of the casting 15 are faired into the round walls of the motor casing so as to lend the device a pleasing appearance. Current may be supplied to the motor through a 35 suitable flexible cable (not shown).

The forward end or nose 15^a of the body casting 15 is notched out as indicated at 15^b (Fig. 1) in order to form a recess dimensioned to embrace the corner juncture between the two angularly disposed metal sheets 10 and 11. Within this 40 notch is mounted a power driven reciprocating metal bending tool shown as a plunger 17 axially reciprocable in a bore 18 fashioned in the body casting 15 (Fig. 2). A suitable bearing sleeve or liner 19 slidably supports the plunger within this 45 bore.

A head 20 (Figs. 2 and 5) is fashioned on the forward end of the plunger 17 for bending and smoothing the sheet metal flange 14 which it contacts. This head is of generally semi-conical 50 shape with a smoothly rounded nose or end. It will be noted that the plunger 17 is disposed for reciprocation along the upper wall of the notch 15^b in the nose of the body casting 15 and the head 20 tapers away toward this wall of the 55

notch. By utilizing a reciprocating plunger head of this shape the flange 14 can be bent and smoothed nicely into position as the tool is moved progressively along the corner juncture between the sheets 10 and 11.

A suitable driving connection is provided within the body member 15 for reciprocating the plunger 17 by the rotatable electric motor 16. This drive connection has been shown as including a speed 10 reduction gearing mounted within a recess 21 (Fig. 2) cored out of the rear end of the casting 15. The speed reduction gearing comprises a pinion 22 on shaft 23 of the motor 16 and meshing with a gear 24 carried by stub shaft 25 journaled in suitable sleeve bearings 26 and 27 in the casting 15 and motor housing. A swash plate 28 fast on the stub shaft 25 meshes with a suitably contoured complementary notch 29 in the plunger 17.

20 In order to locate the metal-working plunger 17 properly with respect to the sheet metal on which it operates guiding abutments have been provided on the tool. This guiding arrangement preferably includes abutments located generally 25 forwardly of the plunger for engagement with the sheet 10 and also an abutment laterally offset from the plunger and engageable with the sheet 11. In the present instance the abutments engaging the sheet 10 are shown in the form of 30 balls 30 journaled in suitable recesses in the lower ends of inverted retaining cups 31, carried by screws 32 threaded in vertical brackets 33 on the nose portion 15^a of the body casting 15 (Figs. 2 and 4). It will be noted that the balls 30 are 35 located on opposite sides of the plunger head 20 and generally forward of its path of travel. The screws 32 may be threaded in and out in order to change the vertical adjustment of the balls 30 with respect to the lower side of the 40 plunger 17 thereby accommodating the tool to sheet metal of different thicknesses. The screws 32 are retained in their adjusted positions by lugs 34 yieldably urged into engagement with the peripherally notched heads 35, on the screws 32, 45 by cantilever supporting springs 36 (Fig. 2).

45 The third guiding abutment which engages the sheet 11 is formed by a ball 37 journaled in a recess 38 fashioned in the front end of an extension 39 on the bottom of the body casting 15. 50 The ball 37 projects through an aperture of smaller diameter in a retaining plate 40 screwed to the front of a projection 39. With the arrangement described, the tool is given a three point 55 rolling contact with the workpiece and can be readily adjusted for use with metal of different gauges.

As a means of supporting the tool while in operation two manual handles are preferably provided. In the construction illustrated these include an inverted pistol-grip handle 41 (Fig. 1) on the forward end of the body member 15 and a U-shaped handle 42 fast on the casing of the motor 16. A suitable control switch 43 for the motor 16 may be included in the handle 42. The handles 41 and 42 are preferably both located substantially on the longitudinal center line of the tool (Fig. 4). With this arrangement either a left or right handed operator can operate the tool with equal ease and use it to work on sheet metal joints located in almost any position. The handles described also serve as a convenient means for carrying the tool about as well as supporting it while in operation.

In the operation of the tool described, the abutment adjusting screws 32 are threaded in or out

until the lower surface of the guide balls 30 are located a distance beyond the lower edge of the plunger head 20 substantially equal to the thickness of the flange 14. The tool is then pressed against the work (in the position shown in Fig. 1) 5 so that the notch 15^b in the nose of the tool embraces the corner of the sheet metal structure which is to be operated upon. The operator then starts the motor 16 so that the plunger 17 is reciprocated at a relatively rapid rate, and moves 10 the tool progressively along the joint between the sheets 10 and 11 as, for example, to the left as viewed in Fig. 4. At each reciprocation of the plunger 17, the portion of the flange 14 in front of it is bent through an angle of substantially 15 90° and pressed flat against the upper surface of the sheet 10. The guide ball 37, below the plunger, is located in such a manner that the reciprocating plunger will occupy substantially the position shown in Fig. 2 at the forward end of its working 20 stroke. It will be noted that in this position the tapered forward portion of the head 20 has passed completely over the flange 14 so that the flange is contacted throughout its length by the cylindrical bottom surface of the plunger and plunger 25 head. By this type of operation the finishing of a joint such as that illustrated can be very quickly and efficiently completed.

Although a particular embodiment of the invention has been shown and described in some 30 detail for illustration of its various novel features, there is no intention to limit the invention to such embodiment but, on the other hand, the appended claims are intended to cover all modifications and alternative constructions 35 within the spirit and scope of the invention.

I claim as my invention:

1. A power actuated portable sheet metal bending tool comprising, in combination, an elongated body member having means thereon for manually supporting the same, the forward end of said body member being notched out to form a recess dimensioned to embrace a corner juncture between two angularly disposed sheets of metal, the walls of said recess being disposed substantially at right angles to each other, a plunger having a metal-bending head thereon, means supporting said plunger for reciprocation along one of said recess walls, a guiding abutment on said body member located generally forwardly of said head and adjustable transversely to the path of reciprocation thereof, a second abutment located adjacent the other of said walls of said recess and displaced laterally from the path of reciprocation of said plunger, 55 said second abutment facing generally axially of said plunger toward the headed end thereof, and power actuated means on said body member for reciprocating said plunger.

2. A power actuated tool for bending sheet 60 metal comprising, in combination, a plunger having a metal-bending head thereon, means supporting said plunger for reciprocation, a guiding abutment on said supporting means located generally forwardly of said head and adjustable transversely to the path of reciprocation thereof, a second guiding abutment on said supporting means laterally displaced from the path of reciprocation from said plunger and facing generally axially thereof toward the headed 70 end thereof, and power actuated means for reciprocating said plunger.

3. A power actuated tool for bending sheet 75 metal comprising, in combination, a plunger having a metal-bending head thereon, means

- supporting said plunger for reciprocation, two guiding abutments on said supporting means located generally forwardly of said head and on opposite sides thereof, means for adjusting said abutments transversely to the path of reciprocation of said head, a third guiding abutment on said supporting means laterally displaced from the path of reciprocation of said plunger and facing generally axially thereof toward the headed end thereof, and power actuated means for reciprocating said plunger.
4. A power actuated portable sheet metal bending tool comprising, in combination, an elongated body member, a plunger mounted for reciprocation on the lower side of said body member, said plunger having a metal-bending head on the forward end thereof, two guiding abutments on said body member located on opposite sides of said head and adjustable transversely to the path of reciprocation thereof, a third guiding abutment on said body member located below said plunger and facing generally axially thereof toward the headed end thereof, and power actuated means for reciprocating said plunger.
5. A power actuated tool for bending sheet metal comprising, in combination, a plunger having a metal-bending head thereon, said head presenting an active face tapering away from the forward end thereof, means supporting said plunger for longitudinal reciprocation, a guiding abutment on said supporting means adjustable transversely to the path of reciprocation of said head, a second guiding abutment on said supporting means displaced laterally from the path of reciprocation of said plunger on the side thereof on which said tapered head face is located and facing generally axially of said plunger toward the headed end thereof, and power actuated means on said supporting means for reciprocating said plunger.
6. A power actuated portable sheet metal bending tool comprising, in combination, a body member having a recess therein, a metal-bending head, means supporting said head on said body member for movement in a fixed path in said recess, a self-contained power actuating device for said head on said body member, a plurality of guiding abutments on said body member disposed at spaced points with relation to said bending head path, and means for adjustably projecting at least two of said abutments into said recess a predetermined distance to determine adjustably the positional relation of said fixed path for the bending head to a work piece inserted in said recess and engaged by said abutments.
7. A power actuated portable sheet metal bending tool comprising, in combination, an elongated body member having manual supporting means thereon and a recess defined by two walls disposed substantially at right angles, a metal-bending head, means supporting said head on said body member for movement in a fixed path in said recess lying generally parallel to one of said recess walls, a self-contained power actuating device for said head on said body member, a plurality of guiding abutments located on said body member projecting into the recess beyond the planes of respective ones of said walls, and means for adjustably shifting at least one of said abutments a predetermined distance beyond the face of the adjacent one of said recess walls to determine adjustably the positional relation of said fixed path for the bending head to a work piece inserted in said recess and engaged by said abutments.

ANDREW M. HEXDALL.
